UNITED STATES PATENT OFFICE

ARCHIBALD G. FLETCHER, OF SPRINGFIELD, MASSACHUSETTS

DAMPER APPARATUS

Application filed February 6, 1930, Serial No. 426,357. Renewed March 7, 1932.

This invention relates to improvements in damper apparatus and is directed more particularly to apparatus for operating flue dampers and the like.

The principal object of the invention resides in the provision of an apparatus for operating dampers which is simple in construction and efficient in operation.

Other objects and advantages of the invention will be observed from the following description thereof in the form at present preferred and which for purposes of disclosure is shown in the accompanying drawing, in which:

Fig. 1 is a front elevational view of the lever operating means forming a part of the invention.

Fig. 2 is a partial sectional elevational view through a flue and showing certain details of construction.

Fig. 3 is a rear elevational view of a housing forming part of the invention.

Fig. 4 is a small scale plan view of a plate for retaining the operating lever in place, and

Fig. 5 is a small scale perspective view of the hub portion of the operating lever showing certain details of construction.

Referring to the drawing, the invention will now be described in detail.

A flue or air duct is represented at 2, which in ordinary practise is run along a wall or between wall forming sections so as to be concealed. In the form of the invention shown the flue is disposed at one side of a wall or partition W and may be an air duct through which it is desired to control the flow of air by a damper 4 which is shown as being in an open position. When closed it will assume a substantially horizontal position.

The damper may take any well known form and has on its opposite sides trunnion blocks 6 and 8 which have trunnions 10 as shown on the block 6 extending therefrom.

A housing 12 as shown in Figs. 2 and 3 is secured to the flue by any suitable means. The housing comprises a hollow body 16 and a cover-plate 18 secured thereto. Lugs 20 extending from the body are secured to flanges 22 of the flue in the embodiment of the invention shown.

A socket member 24 is provided with an outer raceway and is mounted for rotation by means of balls 26 in the housing as shown. The cover plate 18 of the housing has an outwardly projecting hub or boss 19 which is interiorly threaded for receiving a threaded end of a tube 28 which may be of any desired length for extending through the wall W as shown.

A shaft 30 preferably in the form of a square tube extends through the tube 28. Its inner end is receivable in the socket 24 and it in turn receives a squared trunnion 10 of the block 6. A trunnion (not shown) of block 8 is rotatable in a bearing assembly 32 carried by the flue 2. Since the bushing 24 is rotatable in the member 16 the damper may swing between open and closed positions.

Referring to Fig. 3 means will be described for urging the bushing 24 in one direction or in a direction for rotating the damper to a closed position. The housing 16 is provided with a lug 34 projecting inwardly from an opening 36 and a lug 38 extends radially from the bushing 24. Between the lugs a compression spring is disposed and against which the lug 38 acts as the bushing 24 is rotated counter-clockwise. The damper with reference to Fig. 3 swings counter-clockwise to open and therefore opens against the action of the spring which of course tends to urge the damper in a clockwise direction.

A wall plate 44 is provided for securing to the face of a wall by means of screws 46 and has an internally threaded boss or hub 45 so that it may be screwed onto an outer threaded end of tube 28. When screwed onto the tube the screws 46 are screwed into the

wall and the wall plate is held thereby against rotation.

A retaining plate 48 is removably secured to the wall plate by screws 50' in suitable 5 tapped holes in the wall plate and this has a central opening 50 with an inwardly extending lip 52. An operating lever 54 has a cylindrical hub or shaft 56 provided with a cut-away portion 58 longitudinally thereof 10 and a peripheral groove 60, while a squared portion 62 extends from the end thereof and is receivable in the outer end of the square shaft 30.

The lever 54 and plate 48 are assembled 15 by slipping the hub of the lever through the opening of the plate. This may be done by rotating one or the other so that the lip 52 of the plate passes through the cutaway portion 58 of the hub until the lip 52 registers 20 with the groove 60 of the hub when the plate and handle may be rotated relative to one another.

The lever, as shown in Fig. 1, is in a position corresponding to an intermediate position 25 of the damper and swings in a clockwise position when the damper closes. With the retaining plate and lever assembled the hub of the lever is inserted in the tube 28 with its squared end slipped into the square tubular shaft 30. It will be understood that the 30 lever 54 and damper are disposed in correct angular relation for proper operation. The retainer plate is then rotated and secured in place by means of the screws 50'. In this position the lever is held against endwise movement by means of the co-operating lip and groove, the cutaway portion 58 of the lever being out of register with the lip of the plate.

40 A hand grip 62' is pivoted at 64 in the handle 54 and has a pawl portion 66 for engaging with notches 68 on the periphery of plate 44. A spring 70 disposed in a suitable recess of the handle is arranged to urge the 45 pawl portion of the hand grip into locking engagement with the notches.

With the parts assembled as shown the lever 54 is rotated by the hand grip 62'. A counter-clockwise movement of the lever will 50 move the damper from a closed position against the action of the spring 40, while a reverse movement thereof, is accomplished by action of the spring 40 which, will move the damper towards its closed position. By 55 means of the pawl and notches the lever is locked in any desired position, while a raising movement of the hand grip against the action of the spring 70 will permit the lever to be readily rotated in either direction.

60 The trunnion 10 of the block 6 instead of entering the tubular shaft may fit within the sleeve if desired. By means of the construction the damper may be mounted for rotation while the operating parts may be readily connected thereto, whereby the damper may be

swung between open and closed positions and locked in place.

Having described the invention, what I now desire to claim and secure by Letters Patent of the United States is:

1. The combination of a flue and damper oscillatable therein, between open and closed positions with operating mechanism therefor comprising in combination, a housing having a part rotatable therein which is 75 spring pressed in one direction, a trunnion on said damper, a wall plate, an operating member having a hub provided with a circumferential recess and a longitudinal groove, a retaining plate having an opening 80 in which said hub is rotatable and an inwardly extending lip in said recess to hold said operating member and retaining plate against separation except when said groove and lip are in alignment, connections between 85 said member, the rotatable part in said housing and a trunnion on said damper.

2. The combination of a flue at one side of a wall and a damper in said flue with operating means therefor comprising in combination, a housing on said flue having a socket rotatable therein, a wall plate on said wall, a retaining plate on said wall plate provided with an opening having an inwardly extending lip, an operating member 90 rotatable in said opening having a circumferential recess which receives said lip whereby the member and plate are held against separation and provided with a longitudinal groove to permit separation of said 95 plate and member when the lip aligns with said groove, and a member connecting said operating member to a part of said damper 100 within said rotatable socket.

3. The combination of a flue at one side 105 of a wall and a damper in said flue with operating means therefor comprising in combination, a housing on said flue having a socket rotatable therein, a wall plate on said wall, a retaining plate on said wall plate 110 provided with an opening having an inwardly extending lip, an operating member rotatable in said opening having a circumferential recess which receives said lip whereby the member and plate are held 115 against separation and provided with a longitudinal groove to permit separation of said plate and member when the lip aligns with said groove, a member connecting said operating member to a part of said damper 120 within said rotatable socket, and a spring 125 pressed pawl carried by said operating member for engaging teeth carried by said wall plate to hold said member in various positions of adjustment relative to said plate.

4. The combination of a flue at one side of a wall and a damper in said flue with operating means therefor, comprising in combination, a housing on said flue having a socket member rotatable therein, a wall 130

plate on said wall provided with peripheral teeth, a retaining plate on said wall plate having a central opening provided with an inwardly extending lip, an operating member having a hub in said opening which is provided with a circumferential recess receiving said lip and a longitudinal groove to register with said lip to permit separation of said plate and member, a spring pressed pawl on said member for engaging said teeth, and a shaft connected at one end to said operating member and at its other end to said socket member and to a part provided on said damper.

15 In testimony whereof I affix my signature.
ARCHIBALD G. FLETCHER.
